WALTER O. BISCHOFF, OF CHICAGO, ILLINOIS.

AUTOMOBILE CONTROL PEDAL.

Application filed April 19, 1920. Serial No. 374,920.

To all whom it may concern:

Be it known that I, WALTER O. BISCHOFF, a citizen of the United States, and a resident of the city of Chicago, county of Cook and 5 the State of Illinois, have invented certain new and useful Improvements in Automobile Control Pedals, of which the following is a specification, reference being had to the accompanying drawings, forming a part 10 thereof.

This invention relates to improvements in combined accelerator and pedal operated clutch or brake mechanism and particularly in the construction and arrangement of the 15 parts. It consists in the elements and features of construction shown and described, as indicated in the claims.

In the drawings:—

Figure 1 is a perspective view of the device mounted in position relative to the engine casing of an automobile.

Figure 2 is an elevation in part section of the foot pedal member and one of the cams as seen from the side.

Figure 3 is a fragmental plan view showing the two cams.

Figure 4 is a section at the line, 4—4, on Figure 3.

The drawings show a foot board, 1, of an 30 automobile, an engine and transmission box thereof, fragmentally indicated at 2, with a shaft, 3, protruding from the transmission box, 2, through a sleeve, 4, which has secured to its exposed end for rocking it a lever, 5, the shaft, 3, being provided with a lever, 6, for imparting a similar motion to it. Both said levers which extend obliquely upwardly and forwardly of their fulcrums and are normally fitted with rigid foot pedals, are 35 connected, one with the brake mechanism and the other to the clutch mechanism, which mechanisms are housed within the transmission box, 2.

One of the principal objects of the present invention is to interconnect the fuel supply control of the engine with one or the other of the levers just mentioned, and either one is equally well adapted for the purpose. The means herein shown consists of mounting rigidly to the end of the selected lever, 6, a sleeve, 7, of suitable length, within which extends a rotatable spindle, 10, to the upper end of which is secured a foot pedal, 8, of special construction. The pedal may be understood to be made of spring steel to afford whatever advantages may be derived

therefrom; it is shaped to conform somewhat to the contour of the foot of the operator and has engaging lugs, 8^a and 8^b, located at either side thereof, the lug, 8^a, being 60 adjustably mounted to accommodate shoes of variant widths.

The pedal, so mounted is capable of thrusting the lever 6, for operating the mechanism associated therewith, and also for rotating, 65 the spindle, 10, which has an eccentric cam, 11, keyed to the lower end thereof.

In contact with the cam, 11, and in a plane parallel to the thrust thereof is a cam-lever, 12, for controlling the fuel supply. It is 70 mounted in a bracket, 13, for swinging laterally toward and from, and in a plane transverse to that of the rotation of the cam, 11.

The fuel control lever, as seen in Figure 3, comprises a straight portion mounted parallel with the spindle, 10, and having its end curved away as seen at 14; extending at an angle of about 90 degrees from the straight portion thereof is an arm, 15, connected to the fuel supply control device (not 80 shown) by the member, 16, leading thereto; the control device having a spring of usual form which supplies the desired tension in the member, 16, and thereby holds the member, 12, in operative engagement against 85 the contact member, 11.

In the ordinary running of the engine, with the pedal, 8, in its highest position and the automobile in motion, the cams, 11 and 12, stand at the position shown in the drawings in full line, (see Figures 3 and 4), where the cam, 12, rests against the mid portion, 11^a, of the cam, 11. If now it be desired to change the rate of supply of fuel to the carburetor, to either accelerate or retard the engine, the cam, 11, is rotated so that it will contact the lever, 12, at the highest point, 11^b, of the former, thus supplying a maximum quantity, while a partial rotation in the opposite direction will diminish 100 the supply of liquid to the carburetor. For the purpose of limiting the rocking movement of the cam, 11, and prevent its accidental dislodgment, a stop pin, 8^c, mounted on the lower side of the foot pedal, contacts the 105 stop, 7^a, extending radially from the non-rotatable sleeve, 7.

Ordinarily when the pedal is depressed, the fuel supply may be lessened, and for that purpose the lever, 12, is provided with the 110 curved portion, 14, hereinbefore mentioned, and when the pedal is thrust downwardly,

the cam, 11, will travel along the lever toward the curved portion, 14, thereof permitting it to respond to the tension of its spring and occupy a position indicated in 5 dotted line in Figure 3, thus slowing down the engine.

It will, of course, be understood that the fuel control cams are adapted to be connected for co-operating with either the clutch or 10 the brake as desired, and it is intended that the claims be so construed.

I claim:

1. In a motor car having an engine with a fuel supply control, road wheels with brake 15 mechanism therefor, and driven by the engine through a clutch mechanism, an operating pedal for one of said mechanisms, a foot-board having an opening, and said pedal having a stem extending through said 20 opening, the pedal being fulcrumed for thrusting movement of its stem through the opening, and being mounted to rock about the axis of said stem, and operative connections disposed at the under side of 25 the foot-board arranged to transmit the rocking movement of the pedal to the fuel supply control.

2. In combination with a motor car having an engine with a fuel supply control; 30 road wheels with brake mechanism therefor, and driven by the engine through clutch mechanism, an operating pedal for one of said mechanisms, having a stem with a cam thereon mounted for thrust and rocking 35 about the axis of said stem, and a fuel control cam lever fulcrumed adjacent to the said stem, and thereby interconnected for co-operating to control the fuel supply and said pedal-operated mechanism.

3. In combination with a motor car having an engine with a fuel supply control; road wheels with brake mechanism therefor, and driven by the engine, an operating pedal having a stem with a cam thereon, mounted 45 for thrust and rocking about the axis of said stem, and a fuel-control cam-lever fulcrumed adjacent to the same stem and in contact with the cam on said stem, thereby interconnected for co-operating to control the fuel 50 supply and said pedal-operated mechanism.

4. In a motor car in combination with a clutch-operating pedal having a stem and mounted for thrust and rocking about the axis of the stem, a fuel control-lever-ful-

crumed adjacent to the path of said thrust, 55 said stem and lever having co-operating cams by which both the thrust and the rocking of the pedal control the movement of the lever.

5. In a motor car, in combination with a clutch-operating pedal having a stem mounted for thrust and rocking about the axis of the stem, a fuel-supply control-lever fulcrumed adjacent to the path of said thrust; a cam lever integral with the fuel 65 supply control lever, mounted for oscillating toward and from the stem in the plane thereof, and a contact member secured to the end of said stem for co-operating with the said cam lever.

6. In a motor car, in combination with a pedal adapted to control the movement of the vehicle and having a stem mounted to swing about the pedal fulcrum and to rock about its own axis; a fuel supply control 75 lever fulcrumed adjacent to the stem, and an eccentric cam secured to and mounted for rotation with the stem.

7. In a motor car in combination with a clutch-operating pedal having a stem 80 mounted for thrust and rocking about the axis of the stem; a fuel supply control lever fulcrumed adjacent to the path of said thrust; a foot pedal secured to the said stem for the actuation thereof; and a clip adjustably secured to the said pedal for varying the width of the tread of the pedal.

8. In a motor car, in combination with a clutch-operating-mechanism, including a control lever; a sleeve rigidly secured to the 90 control lever for thrust thereof; a stem rotatably mounted in said sleeve; a contact piece secured to the stem and associated with the sleeve for thrust thereof, and a fuel-supply control cam lever arranged to 95 be operated by the said contact piece.

9. In a motor car, in combination with a clutch-operating-pedal having a stem mounted for thrust and rocking about the axis of the stem; a fuel-supply control-lever 100 fulcrumed adjacent to the path of said stem, and a stop pin secured to the pedal co-operating with a stationary stop for limiting the rocking of said pedal and stem.

In testimony whereof, I have hereunto 105 set my hand at Chicago, Illinois, this 9th day of April, 1920.

WALTER O. BISCHOFF.
